UNITED STATES PATENT OFFICE.

ARTHUR PETROV, OF ST. LOUIS, MISSOURI, ASSIGNOR TO ST. LOUIS DOLL AND TOY MANUFACTURING COMPANY, OF ST. LOUIS, MISSOURI, A CORPORATION OF MISSOURI.

VOICE-PRODUCING DEVICE FOR DOLLS.

Application filed November 18, 1925. Serial No. 69,846.

My invention relates to voice producing and controlling device for dolls and more particularly to a device for effectively producing voice sounds uttered by the mouth 5 of a baby, or child, as used in connection with dolls.

The object of my present invention is to provide a voice producing and controlling device which will effectively produce "pa-pa" 10 syllables and "ma-ma" syllables alternately.

A further object of the invention is to provide a voice producing device for dolls which possesses advantages in points of 15 simplicity and efficiency, and, at the same time proves itself comparatively inexpensive in cost of manufacture.

With the above and other objects in view, the invention consists in the novel features 20 of construction, arrangement and combination of parts hereinafter more fully described and finally pointed out in the claims hereto appended.

Referring to the accompanying drawings forming a part of this specification, wherein 25 like characters of reference denote similar parts throughout the several views:

Fig. 1, is a view of a sound production device partly in sectional elevation and partly in side elevation in full lines. The dotted 30 lines illustrate the device in two tilted positions.

Fig. 2, is a longitudinal sectional view of the device.

Fig. 3, is a front elevation of the air expelling head of the bellows that produces 35 "pa-pa" syllables.

Fig. 4, is a front elevation of the air expelling head of the bellows that produces "ma-ma" syllables.

Fig. 5, is a perspective view of the apertured valve bar.

Fig. 6, is a perspective view of the sound producing device.

In carrying out the aim of my invention, 45 I employ a suitable fiber, or equivalent cylindrical tubular casing 1. The wall of the casing 1 is provided intermediate its ends, preferably midway thereof, with a suitable voice or sound outlet opening 2 which is preferably covered by means of a suitable fabric screen 3 to seal the interior of the casing from foreign particles entering 50 the same and yet admit air to the interior

of the casing for supplying the bellows hereinafter described.

Suitable closure caps 4 and 5 are suitably fixed to the ends of the tubular casing 1 and each cap is provided with a centrally disposed elongated socket 6 which is formed by pressing the cap material outwardly at 60 that point.

The numeral 7 represents a suitable flat metallic valve bar which is stationarily supported at each end by causing the reduced ends 7' of the bar to be received in the cap sockets 6 so as to be disposed centrally of the casing 1 and running longitudinally thereof with its center line thereof parallel with the wall of the case 1.

Mounted for alternate sliding movement 70 upon the flat valve bar 7 are a pair of suitably shaped metallic bellows air expelling heads 8 and 9 to which is suitably fixed the inner ends of suitable bellows bags 10 and 11, respectively. The outer ends of the bellows bags are folded over suitable flat rings 12 and 13, respectively, which rings are retained at the outer ends of the tube, but within the same by applying an adhesive to the outer face of the bellows bags adjacent 75 the rings so as to cause the same to adhere to the inner face of the tube 1.

The slidably mounted bellows air expelling heads 8 and 9 are provided with centrally disposed slotted openings 14 and 15, 85 respectively for receiving the stationary valve bar 7 upon which bar the bellows air expelling heads 8 and 9 are alternately slideable and free from possible rotary displacement thereupon. The bellows air expelling heads 8 and 9 are further provided with the air chambers 16 and 17 respectively having the transversely slotted openings 18 and 19, respectively in their lower walls 20 and 21, which openings 18 and 19 register with opposed recesses 22 and 23, respectively, disposed in the bellows air expelling head sections 24 and 25, respectively at the lower side of the valve bar receiving openings 18 and 19 of the bellows air expelling heads 8 90 and 9 respectively.

The bellows air expelling heads 8 and 9 are provided with suitable sound producing reeds 26 and 27, respectively. The reeds 26 and 27 are suitably connected at their inner 105 ends to the inner walls 28 and 29 of the bel-

lows air expelling heads 8 and 9, respectively, and they communicate with the air chambers 16 and 17, respectively through the openings 30 and 31, respectively.

5 The alternately slidable bellows air expelling head 8 is provided in the wall section 32 with a suitable air pressure relief opening 33 communicating directly with the air chamber 34 within the bellows bag 10 to produce sharp voice sounds.

10 The alternately slidable bellows air expelling head 9 is not provided with an air pressure relief opening for the bellows air chamber 35, but in lieu thereof, the wall section 36 of the air expelling head 9 is provided with a suitable air pressure relief opening 37 communicating directly with the air-chamber 17 within the bellows air expelling head 9 so as to cause soft voice sounds.

15 The valve bar 7 which supports the slidable bellows air expelling heads 8 and 9 is provided near one end with the air passages 38 and 39 which cause the uttering of "pa-pa" voice sounds through the reed when the air outlet opening 18 in the lower wall of the air chamber 16 of bellows air expelling head 8 passes the openings 38 and 39 of the valve bar 7, in its outward sliding movement thereon. Opening 38 is transversely disposed while opening 39 is longitudinally disposed and these openings are preferably elongated in shape.

20 The valve bar 7 is provided at its opposite end with the air passage or openings 40 and 41 which cause the uttering of "ma-ma" voice sounds through the reed when the air opening 19 in the lower wall of the air chamber 17 of bellows air expelling head 9 passes the openings 40 and 41 of the valve bar 7 in its outward sliding movement thereon. The opening 40 is transversely disposed while opening 41 is longitudinally disposed and these openings are preferably elongated.

25 Openings 38 and 40 are transversely disposed to sharpen and make quicker the first "pa" and "ma" syllables respectively produced thereby while the openings 39 and 41 are longitudinally disposed and elongated to draw out and lengthen the second "pa" and "ma" syllables, respectively produced thereby.

30 The bellows air expelling heads 8 and 9 are slidably mounted independent of each other upon the valve bar 7 in opposed relation to each other, and so disposed and spaced with relation to each other that they will not come into contact with each other when at their inner most positions. The air expelling heads of the bellows both slide in the same direction at the same time when the casing 1 is tilted in either direction, as indicated in dotted lines A and B in Fig. 1, so that while one bellows is producing "pa-pa" syllables when tilted to position des-

ignated A, the other bellows which produces "ma-ma" syllables is filling with air to be compressed therein when the casing 1 is tilted in the opposite direction, designated B.

35 The operation of the sound producing and controlling device is as follows:

40 When the device is tilted to the dotted line position shown in Fig. 1, by the reference character A, from its full line position, the air expelling head 8 will slide to its downward position upon the valve bar 7 causing the air to pass through the reed 26 into chamber 16 and through opening 18 and out of the valve bar openings 38 and 39 thereby causing the reed to produce "pa-pa" syllables. The opening 33 in the head wall 32 relieves the pressure within the bellows bag 10 so as to prevent the closing of the reed and yet only relieve enough pressure to provide a sharp sound at the reed in producing "pa-pa" syllables.

45 When the device is tilted to the opposite dotted line position, as shown by reference character B, the air expelling head 9 will slide to its downward position upon the valve bar 7 causing the air to pass through the reed 27 into chamber 17 and through opening 19 and out of the valve bar openings 40 and 41 thereby causing the reed to produce "ma-ma" syllables. The opening 37 in the head wall 36 relieves the air pressure with the head chamber 17 sufficient to soften the sound of the reed 27 in producing "ma-ma" syllables.

50 It will be apparent that when air is being compressed within the bellows bag 10 that the bellows bag 11 is taking in air.

55 The many advantages of the herein described invention will readily suggest themselves to those skilled in the art to which it appertains.

60 I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed.

65 What I claim is:

70 1. A device of the class described consisting of a hollow casing having an opening, a valve bar, spaced aligned movable air expelling means mounted upon the valve bar, sound producing means on the air expelling means, valve means on the valve bar and the movable air expelling means cooperating with the sound producing means to interrupt and articulate the sound from the sound producing means to effectively produce audible

"pa-pa" syllables when the device is tilted in one direction and which will effectively produce audible "ma-ma" syllables when the device is tilted in the reverse direction.

2. In a sound producing device including a casing having an opening, a stationary valve bar having two sets of openings, sound producing means, alternately slideable sound controlling means cooperating with one set of the valve bar openings for effectively producing "pa-pa" syllables when said sound controlling means is moved past said set of openings and alternately slideable sound controlling means cooperating with the other set of valve bar openings for effectively producing "ma-ma" syllables when said latter sound controlling means is moved past said latter set of valve bar openings.

3. A voice sound producing device including a casing having an opening, a stationary valve bar, a pair of sound controlling devices each including a member movable upon the valve bar, a sound producing device carried by each movable valve means on the valve bar and the movable member cooperating with the sound producing devices to interrupt and articulate the sounds from the sound producing devices to produce "pa-pa" syllables when one of the movable members is moved along the valve bar in one direction and to produce "ma-ma" syllables when the other movable member is moved along the valve bar in the opposite direction.

4. A sound producing and controlling device comprising a tubular casing having closed ends and a sound emitting opening intermediate the ends of the casing, a flat valve bar fixed within the casing, a pair of bellows alternately slideable upon said bar, sounding means, and valve means on the valve bar and the bellows cooperating with the sounding means to interrupt and articulate the sounding means to effectively produce "pa-pa" syllables when the casing is tilted in one direction and effectively produce "ma-ma" syllables when the casing is tilted in the opposite direction.

5. In a device for producing voice sounds embodying a tubular member, a fixed valve bar within the tubular member, a pair of sound producing devices, a pair of sound controlling members having valve openings alternately slideable upon said valve bar in spaced relation, said valve bar having spaced openings for register with the valve opening in one of the sound controlling members for emitting "pa-pa" syllables when the tubular member is tilted in one direction and said valve bar having spaced openings therein for register with the opening in the other sound controlling member for emitting "ma-ma" syllables when the tubular casing is tilted in the opposite direction.

6. A device for producing voice sounds for talking dolls embodying a tubular casing

closed at opposite ends and having a sound opening in its wall intermediate the ends of the casing, a valve bar fixed within the casing, a pair of bellows bags fixed at their outer ends to the ends of the casing, an air expelling head fixed to the inner ends of the bellows bags and slidably mounted upon the valve bar in spaced relation, sounding means carried by the air expelling heads and valve means on the valve bar and air expelling heads cooperating with the sounding means to interrupt and articulate the sounds from the sounding means to produce "ma-ma" sounds when the doll is tilted in one direction and to produce "pa-pa" sounds when the doll is tilted in the opposite direction.

7. In a sound producing device for dolls which will give "pa-pa" and "ma-ma" sounds, a tubular casing having an opening intermediate its ends, closure caps for the ends of said casing, a socket formed in each closure cap, a valve bar receivable at its ends in the cap sockets fixedly positioning the valve bar against rotation and displacement with relation to the center line of the casing, said valve bar having valve openings therein arranged in spaced pairs, one pair of openings being spaced further apart than the other pair of openings, a pair of opposed air expelling heads having valve openings therein and alternately slideable upon said valve bar, sound producing means on each air expelling head and a bellows bag fixed at one end to each air expelling head and at their opposite ends to the casing.

8. In a sound producing device for dolls, a hollow casing having a wall opening, a stationary valve bar, a pair of bellows bags, an air expelling head fixed to the inner end of each bellows bag, one of said air expelling heads having an air pressure relief opening, sound producing means carried by each air expelling head, valve means on the valve bar and each air expelling head cooperating with the sound producing means to interrupt and articulate the sound from the sound producing means to give "pa-pa" sounds when the casing is tilted in one direction and to give "ma-ma" sounds when the casing is tilted in the opposite direction.

9. A device of the class described comprising a hollow casing closed at its ends and having a wall opening therein, a flat valve bar stationarily supported at opposite ends by the ends of the casing, a pair of air expelling heads slidably mounted upon said valve bar, sounding means carried by the air expelling heads, a bellows attached at one end to each air expelling head at its opposite end to the casing, valve means on the valve bar and the air expelling heads cooperating with the sounding means to interrupt and articulate the sound from the sounding means to give "pa-pa" sounds

when the casing is tilted in one direction and to give "ma-ma" sounds when the casing is tilted in the opposite direction.

10. In a sounding device, a casing, a slide bar, a pair of spaced aligned air expelling members one of which is provided with an air pressure relief opening slidably mounted upon the slide bar, sounding means carried by the air expelling members and valve means on the slide bar and the air expelling members cooperating with the sounding means to interrupt and articulate the sound from the sounding means upon the tilting of the device in either direction.

15. 11. In a sounding device, a casing, a slide bar, a pair of spaced aligned air expelling members one of which is provided with an air pressure relief opening slidably mounted upon the slide bar, sounding means carried by the air expelling members, valve means on the slide bar and the air expelling member having the air pressure relief opening cooperating with its respective sounding means to interrupt and articulate the sound from the sounding means to produce "pa-pa" sounds when the device is tilted in one direction and valve means on the slide bar and the other air expelling member cooperating with its respective sounding means to interrupt and articulate the sound from said sounding means to produce "ma-ma" sounds when the device is tilted in the opposite direction.

12. In a device of the class described, a casing, a stationary slide bar, sound controlling members slidably mounted upon said bar, bellows attached to the sound controlling members, sounding members applied to said sound controlling members, valve means on the valve bar and the sound controlling members cooperating with the sounding members to interrupt and articulate the sounds from the sounding means to give "pa-pa" syllables when the casing is tilted in one direction and to give "ma-ma" syllables when the casing is tilted in the opposite direction.

13. The combination of a casing having a sound outlet opening in its side wall, a flat valve bar fixed within the casing, a pair of bellows alternately slidable upon the valve bar, a sound producing device carried by each bellows, valve means on the valve bar and one of the bellows cooperating with its respective sound producing device to interrupt and articulate said sound producing device to produce "ma-ma" syllables when air is expelled from said bellows, valve means on the valve bar and the other bellows cooperating with its respective sound producing device and said latter bellows having an air relief opening leading into the casing for reducing the air pressure against said latter sound producing device by more

quickly expelling the air from the latter 65 bellows whereby "pa-pa" syllables are produced.

14. In a device for producing sounds of different articulation, a tubular member having a sound outlet opening, a supporting member within the tubular member having two sets of openings therein, a musical member having a sound outlet opening slidably mounted for alternate movement upon said bar to permit passing register of the sound outlet opening of the musical member with the one set of openings in the bar to produce "ma-ma" syllables and a second musical member having a sound outlet opening 70 75 80 slidably mounted for alternate movement upon said bar to permit passing register of said sound outlet opening with the other set of openings in the bar and said musical member having in addition an air relief opening leading into the tubular member to 85 quicken the sliding movement of said latter musical member upon the bar thereby causing "pa-pa" syllables to be produced.

15. In a device for producing sounds of different articulation, an apertured tubular member, an apertured support, air expelling members slidably mounted upon said support, sound producing means carried by each air expelling member, one of said air expelling members having an air escape opening leading directly into the casing causing the production of "pa-pa" syllables upon 90 95 100 105 110 115 120 ling means whereby to produce a quickened movement thereof upon the support thereby producing "pa-pa" syllables.

18. A device of the class described, consisting of a hollow casing having an opening, a valve bar, spaced aligned movable air expelling means mounted upon the valve bar, one of said air expelling members being provided with an air pressure relief opening, sound producing means on the air expelling means, valve means on the valve bar and the movable air expelling means co-operating with the sound producing means

to interrupt and articulate the sound from the sound producing means carried by the air expelling member having the air pressure relief openings to effectively produce audible "pa-pa" syllables when the device is tilted in one direction and which other sound producing means will effectively produce audible "ma-ma" syllables when the device is tilted in the reverse direction.

In testimony whereof, I have hereunto signed my name to the specification.

ARTHUR PETROV.
